JUG OR SIMILAR ARTICLE

Floyd E. Pettengill, Lancaster, Ohio, assignor to Anchor Hocking Glass Corporation, Lancaster, Ohio, a corporation of Delaware

Filed June 1, 1966, Ser. No. 2,506

Term of patent 14 years

(Cl. D9—49)

FIG. 1 is a front elevational view of a jug or similar article showing my new design;

FIG. 2 is a side elevational view;

FIG. 3 is a sectional view on an enlarged scale taken along line 3—3 of FIG. 1; and

FIG. 4 is a sectional view on an enlarged scale taken on the line 4—4 of FIG. 1.

The dominant features of my design reside in the portions shown in full lines.

I claim:

The ornamental design for a jug or similar article, substantially as shown and described.
